J. C. Barstow, of Providence, R. I.
Letters Patent No. 1063, Dated Nov 16, 1858.

The schedules referred to in these Letters Patent and making part of the same.

To all Persons to whom these Presents shall come:

Be it known that J. C. Barstow, of Providence in the County of Providence and State of Rhode Island, have invented or produced a new and useful design for a Cooking Stove, and I hereby declare that the said new design is fully described and represented in the following Specification and accompanying drawings to which reference is hereinafter made.

The figures of the accompanying plates of drawings represent my new design. In plate 1, fig. 1. is an elevation of the side plate of the stove, and fig. 2. is a section of the same taken in the plane of the line A.B. fig. 1. In plate 2, fig. 3. is an elevation of the front plate.

The oven door a. a. of the side plate, fig. 1, plate 1. has around its sides the moldings b. b. and in its center the raised gothic figures c. c. The panel d. d. has a gothic figure e. e. and the small door f. f. has a similar one. On the top edge of the plate are the small gothic ornaments g. g. and on the bottom the gothic ornaments h. h. and on the sides the raised figures k. k.

The doors l. l. of the front plate are ornamented with moldings i. i. and gothic figures m. m. the top will be the gothic ornaments g. g. and the sides with the raised figures k. k.

Having thus described my new design, I shall state my claim as follows: That I claim as my invention and desire to have secured to me by letters Patent, is the new design for a cooking stove consisting of the ornamental configurations herein above described and represented in the drawings.
